J. CUSTER

FURNACE

Filed Aug. 17, 1926

Patented May 8, 1928.

1,668,585

UNITED STATES PATENT OFFICE.

JOHN CUSTER, OF DETROIT, MICHIGAN.

FURNACE.

Application filed August 17, 1926. Serial No. 129,690.

My invention relates to a new and useful improvement in a furnace, and has for its object the provision of a furnace in which a maximum amount of heating surface is afforded in proportion to the size of the grates used.

Another object of the invention is the provision of a furnace in which the draft will be directed downwardly through the combust- 10 ing fuel and thence outwardly through the flue.

Another object of the invention is the provision of a furnace in which the gases are retarded in their passage from the fur- 15 nace to the outlet flue and in which a thorough mixing of the gases with air is effected for completing to the maximum the combustion of the gases.

Another object of the invention is the pro- 20 vision of a furnace, in which the draft on the furnace is reduced to a minimum, thus effecting a retarding while at the same time also completely combusting the gases from the fuel.

Another object of the invention is the pro- 25 vision in a furnace of an auxiliary fire box in which partially burned fuel deposited therein from the main fire box may continue to burn, thus resulting in an economy of fuel 30 consumption.

Another object of the invention is the pro- 35 vision of a furnace which will be simple in structure, economical of manufacture, and highly efficient in use and quite economical in fuel consumption.

Other objects will appear hereinafter.

The invention consists in the combination and arrangement of parts hereinafter described and claimed.

The invention will be best understood by a reference to the accompanying drawings which form a part of this application and in which,

Fig. 1 is a central vertical sectional view 45 of the invention.

Fig. 2 is a front elevational view of the invention.

Fig. 3 is a side elevational view of the invention with parts broken away and parts 50 shown in section.

Fig. 4 is a sectional view taken on sub- 55 stantially line 4-4 of Fig. 3.

Fig. 5 is a sectional view taken on sub- 55 stantially line 5-5 of Fig. 3 with parts broken away.

The furnace comprises a housing or cas-

ing having outer side walls 8 and 9, an outer rear wall 10, and inner side walls 11 and 12 connected by an inner rear wall 13. The side walls 8 and 11 are connected by a front 60 wall portion 14 and the side walls 9 and 12 are connected by a front wall portion 15, the inner side walls and the inner rear wall being spaced from the outer side walls and the outer rear wall respectively. A top wall 65 is provided, a portion of which inclines upwardly to the front as shown at 16, an inclined door 17 being mounted thereon for closing the space between the edge of the upper wall 16 and the front wall. A venti- 70 lating slide 18 is provided in the door 17 for opening and closing the openings 19 so as to regulate the admission of air into the furnace. Mounted between the front wall and the auxiliary rear wall 13 is an upper grate 75 20 upon which the fuel is deposited through the door 17. Formed in the side walls 11 and 12 are openings 21 which are formed by punching inwardly a portion of the side walls 11 and 12 as shown in Fig. 5. Mount- 80 ed between the side walls 8 and 11 and be- 85 tween the side walls 9 and 12 are channel irons 22 and 23 respectively which are formed arcuate as clearly shown in Figs. 1 and 3 in- 90 clined forwardly and upwardly. Projecting upwardly from the base 24 is a partition 25 connected by the plate 26 to the wall 13. Mounted on the forward wall of the casing and on the partition 25 is a lower or auxil- 95 iary grate 27. A stoker door 28 serves as a 95 closure for the opening 29 formed in the front wall. A door 30 serves as a closure for the opening 31 formed in the front wall and a door 32 serves as a closure for the opening 33 formed in the front wall, this opening 33 being positioned slightly above the base or bottom 24. The grates are all of the rock- 100 able type but since these grates of themselves form no specific part of the present invention they are not shown in detail. The upper grate 20 is mounted on a downwardly 105 projecting portion 34 of a bracket 35 which is mounted on the wall 13, and the forward end of the grate 20 is journalled in a down- 110 wardly projecting portion 36 of a bracket 37 which is mounted on the front wall of the furnace and which is provided with the lug 38.

In operation the fuel is deposited through the door 17 on the grate 20 and there ignited. Communicating with the space between the wall 13 and the rear wall 10 is a pipe or out-

let flue 39 connecting with which is the pipe 40, in which is positioned a suitable damper 41. Upon starting the furnace the slide 18 will be moved so as to uncover the openings 19, thus permitting air to enter the upper part of the furnace. In starting, the closure 42, which serves to close the opening 43 formed in the rear wall 13, will be raised by means of the rod 44, which is provided with suitable notches 45, so that the air passing through the door 17 will pass through the fuel on the grate 20, through the opening 43 and thence outwardly through the pipe 40. If desired the door 28 may be opened for the admission of more air into the upper part of the furnace. After the fuel on the grate 20 has become ignited the closure 42 is moved to closed position and the air entering through the door 17 will pass downwardly through the fuel on the grate 20 and through the openings 21 into the space between the side walls 8 and 11 and the side walls 9 and 12 being deflected upwardly and forwardly by the channel irons 22 and 23 so as to pass over the ends of these angle irons into the space between the rear walls 10 and 13 and thence outwardly through the pipe 40. In this way the area of the side walls and the rear wall is presented as a heating surface and the gases are retarded in their passage from the furnace by the baffling thus provided. The slide 18 may be regulated to admit the desired quantity of air into the furnace, the damper 41 being, of course, open. After the fuel has become well ignited the damper 41 may be closed and experience has shown that when this damper 41 is entirely closed the space around the periphery of the damper and the opening in its center will be sufficient to permit proper combustion of the fuel and prevent escape of gases from the furnace other than through the flue 40.

The location of the gate 27 below the grate 20 is such that unburned fuel falling from the grate 20 is deposited thereon and is permitted to burn further so that complete combustion of the fuel takes place and the deposit of charred fuel, such as coke and the like in the ash pit, is eliminated.

The provision of the space below the grate 20 and below the grate 27 is such as to effect a thorough commingling of the various gases with effect and with the air admitted so that the maximum combustion is effected and economy in fuel consumption thus obtained.

As shown the furnace is mounted on suitable supports 57 which comprise angle irons for reinforcing the corners of the furnace. Cleanout doors 58 and 59 are provided on the front wall.

The furnace may be used for heating by radiation, hot air, hot water or the like, slight modifications, of course, being necessary from the structure shown in the draw-

ings in order to accommodate the furnace for steam or hot water heating. These modifications, however, would be obvious to one skilled in the art and for that reason are not shown.

While I have illustrated and described the preferred form of my invention, I do not wish to limit myself to the precise form of structure shown, but desire to avail myself of such variations and modifications as may come within the scope of the appended claims.

Having thus described my invention what I claim as new and desire to secure by Letters Patent is:

1. A furnace of the class described comprising: an outer casing having side and rear walls; an inner casing having side and rear walls spaced from the side and rear walls of said outer casing; a grate mounted in said inner casing, said inner casing being in communication with the space between said side walls through openings formed in the side walls of said inner casing below said grate, said inner casing having an air inlet positioned above said grate. 80 85 90

2. A furnace of the class described comprising: an outer casing; an inner casing enclosed by said outer casing, the side and rear walls of said inner casing being spaced from the side and rear walls of said outer casing; an outlet flue communicating with the space between said rear walls; baffle members mounted in the space between said side walls, said inner casing communicating through openings with the space between said side walls; a grate mounted in said inner casing above said openings, said inner casing having an air inlet opening positioned above said grate. 95 100 105

3. A furnace of the class described comprising: an outer casing; an inner casing enclosed by said outer casing, the side and rear walls of said inner casing being spaced from the side and rear walls of said outer casing; an outlet flue communicating with the space between said rear walls; baffle members mounted in the space between said side walls, said inner casing communicating through openings with the space between said side walls; a grate mounted in said inner casing above said openings, said inner casing having an air inlet opening positioned above said grate; and an auxiliary grate positioned in said inner casing below said communicating openings, said auxiliary grate being adapted for reception of fuel falling from said first mentioned grate, said grates being adapted for retention of fuel during combustion. 110 115 120

In testimony whereof I have signed the foregoing.

JOHN CUSTER.
